ATTACHMENT FOR THE CUTTER BARS OF
MINING MACHINES

George C. Watson, Denver, Colo.

Application March 7, 1949, Serial No. 80,031

3 Claims.

(Cl. 262—28)

1

This invention relates to a method of mining coal, and to means for carrying out the method. Former methods of mining coal embodying the use of explosives and expanding gases have resulted in a large percentage of fine coal or slack. This fine coal in some localities had commercial value in pulverized coal plants. With the increasing use of gas and oil fuels, however, the market for slack coal has been depleted and the slack has become pure waste for the mines.

The principal object of this invention is to provide a method of mining coal, and means for carrying out the method which will produce a minimum of slack and a maximum of lump coal.

Another object of the invention is to provide an attachment for conventional coal-cutting machines which will enable the same operation of the machine to make two cuts, where before only one was possible.

A still further object is to provide means for breaking down and removing cut coal without the use of explosives.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side view of a conventional coal-cutting machine, illustrating the invention applied thereto;

Fig. 2 is an enlarged top view, looking down along the line 2—2, Fig. 1, with the coal-cutting chain employed in the invention removed to illustrate the means for applying the improved cutter to the conventional machine;

Fig. 3 is a longitudinal section, taken on the line 3—3, Fig. 2;

Figs. 4, 5, and 6 are cross-sections, taken on the lines 4—4, 5—5, and 6—6, respectively, Fig. 3.

Fig. 7 is a view of a typical coal face cut by the use of the improved machine;

Fig. 8 is a vertical section of the coal face, taken on the line 8—8, Fig. 7;

Fig. 9 is an enlarged, sectional view of a horizontal kerf, illustrating a coal-removing device used with the improved method;

Fig. 10 is a similar section, illustrating a coal-breaking device used with the present method;

Fig. 11 is a detail, perspective view of the coal-removing device of Fig. 9;

2

Fig. 12 is a rear end view of the breaking device of Fig. 10;

Fig. 13 is a longitudinal section of the breaking device, taken on the line 13—13, Fig. 12; and

Fig. 14 is a similar section, illustrating the breaking device in the expanded position.

In the drawings, typical parts of a conventional coal cutter are designated by numeral as follows: motor box 15, track wheels 16, turntable 17, swinging boom 18, cutter head 19, operator's cab 20, boom axle 21, and tracks 22. The cutter illustrated is designed for track use. Similar cutters are used on "Caterpillar" and truck wheel mountings for trackless mines. Such a machine is designed so that the boom 18 can be raised from the position of Fig. 1 to any desired vertical angle about the axle 21. It can also be rotated about the vertical axis of the turntable 17 to either side of the machine. The cutter head 19 is rotatably mounted about the longitudinal axis of the boom 18 so that it may be rotated around the axis of the boom.

The cutter head 19 usually supports a single cutter bar in the position indicated by broken line at 23, Fig. 1. The chain of the usual cutter bar is driven from a drive cutter chain sprocket 24. The usual bar is supported from a backbone bar 25 mounted in a step plate 38 on the cutter head 19.

For the purposes of this invention, the usual cutter bar and its cutter chain are removed from the machine, leaving the backbone bar 25 and chain sprocket 24 in place thereon.

This invention employs a bearing frame 26 which is forked at its inner extremity to slide over the projecting portion of the backbone bar 25, where it is clamped in place by means of suitable clamping bolts 27. The frame 26 and the bar 25 are maintained in axial alignment with each other by means of cotter keys 28 sliding in key ways in both the bar and the frame. The bolts 27 extend through longitudinally slotted bolt slots 29 in the bar 25.

The frame 26 supports two forwardly extending fork plates 30 which are welded or otherwise secured to the frame 26 so as to form an integral part thereof. The frame 26 supports a sprocket shaft 31 mounted in suitable anti-friction bearings 32. The sprocket shaft 31 carries a driven chain sprocket 33 at its middle, within the confines of the frame 26, and carries a cutter chain sprocket 34 at each of its extremities.

A drive chain 35 is trained about the driven sprocket 33 and about the standard cutter chain sprocket 24 of the cutter head 19. The tension in the chain 35 can be regulated by means of an adjusting screw 36 which is threaded through the

frame 26 into contact with the end of the backbone bar 25. After the proper adjustment has been made, the bolts 27 are tightened to retain the frame in the adjusted position.

Each of the fork plates 30 carries a step plate 31 similar to the usual step plate 38 with which conventional cutter heads 19 are provided. The step plates 37 and 38 are standard equipment and are designed to support the backbone bars 25 and the cutter bars of a conventional coal-cutting machine.

With the present arrangement, however, two cutter bars are supported in place of the former single bar which was mounted upon the backbone bar 25 and the step plate 38. The new double cutter bars are indicated at 39. They are slid in place over bar plates 40 which are in turn permanently mounted on the step plates 37. The bars 39 are of the usual construction and comprise two side plates spaced apart by means of runner strips 41, against which the backs of the links of a pair of cutter chains 42 travel, as in the usual coal-cutting machine.

In this improved attachment, however, the cutter chains 42 are trained around the newly added, spaced-apart sprockets 34, and it can be readily seen that this provides two parallel, uniformly spaced cutter chains 42 at each side of the position 23 formerly occupied by the single cutter chain. It can also be seen that no changes are required in the operating mechanism of the coal cutter, since the new chains 42 are still driven from the former cutter chain drive sprocket 24 through the medium of the chain 35.

In carrying out the objects of the improved coal mining method, the two parallel cutter bars 39, with their traveling cutter chains 42, are moved horizontally across the coal face to produce a plurality of parallel, spaced-apart, horizontal kerfs 43, as shown in Figs. 7 and 8, to divide the face into spaced, horizontal layers 45 connected at the back to the unbroken face, and at the sides to the side walls or pillars of the room.

In actual practice the chains are positioned about 18 inches apart, and the cutter bars are approximately seven feet long, so that the blocks or layers 45 measure 18" x 84" by the full width of the room. In this improved method, the blocks or layers may be broken from their anchorage at the wall and the pillars into large, easily handled blocks of coal, and are pulled forward so that they may be handled by a loading machine as follows:

A plurality of hook plates 46, having cables 47 attached thereto, are driven back into the bottom kerf 44 and at intermediate points, as shown in Figs. 7 and 9. The hook plates 46 are provided with outwardly extending hooks 48. Expanding devices are then forced into the kerfs at their points of connection with the pillars, as indicated in Fig. 7, to break the blocks loose from their side supports and allow them to fall upon the hook plates 46. The cables 47 are then drawn upon, the hooks 48 engaging the blocks, to pull the blocks forwardly to a position where they can be gathered by the loading machines.

An expanding device for breaking the blocks loose from the wall and pillars is illustrated in Figs. 12, 13, and 14. The device comprises two hollow, inclined, wedge jaws 49 hinged together at their forward extremities upon a hinge pin 50 so that they may swing away from each other at their rearward extremities. A wedge member 51 is mounted between the jaws and provided with a socket for receiving the extremity of a drill steel 75

52. The jaws are constantly urged together by means of suitable tension springs 53.

In use, the expanding device is pushed inwardly in the horizontal kerfs 43 until the extremity of the cut is reached, as shown in Fig. 10. The drill steel 52 is then driven inwardly either by hand or through the medium of an electric or pneumatic hammer to force the wedge member 51 forwardly, as shown in Fig. 14. This causes the two jaws 49 to expand from each other so as to break the coal blocks from their attachment. The wedge member 51 may be locked to the extremity of the drill steel 52 by means of a cross pin 54 riding in a slotted hole 55 in the drill

steel. While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. An attachment for coal-cutting machines having a cutter head carrying a chain drive sprocket, comprising: a backbone bar extending from said cutter head; a bearing frame slidably engaging said bar; a chain sprocket shaft carried by said frame; a drive sprocket on said sprocket shaft within said frame; a drive chain trained about said drive sprocket and about said cutter chain sprocket; additional cutter chain sprockets mounted on the extremities of said sprocket shaft; a coal cutter chain extending from each of the additional sprockets; and means for supporting said latter chains in parallel, spaced-apart relation.

2. A double cutter chain attachment for coal cutting machines, comprising: a hollow bearing frame; a sprocket shaft journaled in said bearing frame, extending through the hollow therein and projecting from both sides thereof; a drive sprocket on said shaft within the hollow bearing frame; a cutter bar extending from each side of said frame in parallel relation; a cutter chain sprocket mounted on each extremity of said sprocket shaft; a coal cutter chain supported by each cutter bar and driven from one of said cutter chain sprockets; and means for attaching said frame to a coal cutting machine.

3. A double cutter chain attachment for coal cutting machines, comprising: a hollow bearing frame; a sprocket shaft journaled in said bearing frame, extending through the hollow therein and projecting from both sides thereof; a drive sprocket on said shaft within the hollow bearing frame; a cutter bar extending from each side of said frame in parallel relation; a cutter chain sprocket mounted on each extremity of said sprocket shaft and a coal cutter chain supported by each cutter bar and driven from one of said cutter chain sprockets, said bearing frame having a receiving socket adapted to be slid over a projecting member on said coal-cutting machine to support said frame thereon.
